V. L. JACOBSEN.

SAVINGS BANK.

APPLICATION FILED DEC. 20, 1919.

1,412,526.

Patented Apr. 11, 1922.

Inventor:
Victor L. Jacobsen,
by
Spurr, Marshall & Suzzallo,
Attorneys.

UNITED STATES PATENT OFFICE.

VICTOR L. JACOBSEN, OF CLEVELAND, OHIO.

SAVINGS BANK.

1,412,526.

Specification of Letters Patent. Patented Apr. 11, 1922.

Application filed December 20, 1919. Serial No. 346,419.

To all whom it may concern:

Be it known that I, VICTOR L. JACOBSEN, a citizen of the United States, resident of Cleveland, county of Cuyahoga, and State 5 of Ohio, have invented new and useful Improvements in Savings Banks, of which the following is a specification, the principle of the invention being herein explained and the best mode in which I have contemplated 10 applying that principle, so as to distinguish it from other inventions.

My invention relates to portable savings banks adapted to receive and hold coins, its object being to provide a device of the above 15 described character which will be simple and compact in form, so that it may be readily and conveniently carried in the pocket.

The said invention consists of means hereinafter fully described and particularly set forth in the claim.

The annexed drawing and the following description set forth in detail certain means embodying my invention, the disclosed 25 means, however, embodying but one of the various mechanical forms in which the principle of the invention may be applied.

In said annexed drawing:

Figure 1 represents a side elevation of a 30 device embodying my invention.

Figure 2 represents an end elevation of such device.

Figure 3 represents a fragmentary section upon an enlarged scale, taken upon 35 the plane indicated by line III—III in Figure 1.

Figure 4 represents a plan of the device upon an enlarged scale.

Figure 5 represents, upon an enlarged 40 scale, a horizontal section taken upon the plane indicated by line V—V in Figure 1 and viewed in the direction indicated by the arrows.

Figure 6 represents, also upon an enlarged 45 scale, a fragmentary vertical section taken upon the plane indicated by line VI—VI in Figure 5.

Figure 7 represents a horizontal section taken upon the plane indicated by line 50 VII—VII in Figure 6, and viewed in the direction indicated by the arrow.

Figure 8 represents an elevation view of a key used in connection with the locking device forming part of the device.

55 The illustrated embodiment of my invention includes a coin holder 1, which is made

preferably of thin sheet metal forming sides and ends, together with a central sheet metal element 2 which constitutes a partition. Divisional walls 3 are provided, in this case 60 two sets, which form a plurality of magazines 4 upon opposite sides of the partition 2. These magazines are parallel and each comprises a compartment 5 having a thickness substantially equal to the thickness 65 and width of the coin which it is adapted to receive. Figure 1 illustrates a full sized embodiment of my invention adapted to receive dimes.

The upper end 6 of each magazine is open 70 and forms an entrance opening, adjacent to each of which is a small projection 7 which permits the entrance but prevents the withdrawal of the coin after having been inserted in the compartment. The bottom of each compartment is open, Figure 6, and forms a discharge opening for the coins. It will be noted that inasmuch as the compartments are of a depth substantially equal to the thickness of the coins, the latter are held in 80 position in the magazine end to end, that is, with their circumferences in contact, as shown in Figure 1.

The outer wall of each magazine is cut out as at 8 in Figure 1, such cut out portion 85 being of less width than the coin and of less length than the compartment. The provision of this cut out portion permits of access to the coins whereby the latter may be shifted or pushed and moved through the 90 magazine.

While the device is performing its function as a savings bank, the discharge openings are closed by means of a locking device which, in the illustrated embodiment of my invention, comprises a member 9, Figures 6 and 7, provided with top, bottom, side and end walls whereby the interior enclosed space 10 is formed. The ends 11 of this member 9 are provided with extensions 12, which are adapted to embrace the lower end 95 of the coin holder. Upon the interior of the member 9 is secured a standard 13 which forms a bearing for a plunger 14. This plunger projects laterally from the adjacent side of the member 9, and is formed with an upward projection 15 provided with an inwardly projecting member 16. This latter member 16 is adapted to pass through an opening 17 in the adjacent wall of the coin 100 holder. The plunger is further provided with a collar 18 between which and the stand-

ard 13 is placed a coil spring 19 normally in a state of compression. The inner end of the plunger is provided with a shoulder 18^a and an adjacent beveled portion 19. This shoulder is normally engaged by a lug 20 forming the end of a spring member 21 which has its other end fixedly mounted on a cross piece 22 secured within the compartment 10 of the member 9.

10 The other end of the member 9 is provided with a fixed member 23 projecting upwardly and provided with an inwardly projecting portion 24 adapted to enter an opening 25, in the adjacent portion of the coin holder.

15 A key hole 27, Figure 1, is provided into which a key 28 may be inserted, the actuation of which will lift the spring detent 21 and thus permit the plunger 14 to be actuated by the spring 19 and disengage the inwardly projecting portion 16 from the coin holder. This will permit, as will be readily

understood, the member 9 to be removed from the lower end of the coin holder and the coins to be discharged therefrom manually.

25

What I claim is:

A savings bank comprising a body portion having an elongated compartment of transverse dimensions corresponding substantially to the diameter and thickness of a particular coin, said compartment being open at both ends; means within said compartment adjacent one end adapted to permit insertion of coins but preventing removal thereof through said open end; a removable closure for closing the opposite end of said compartment; and a lock for securing the closure in place.

Signed by me this 13th day of December, 1919.

VICTOR L. JACOBSEN.
